HEAD SHEAVE BLOCK FOR CLAMSHELL
BUCKET OR THE LIKEEdward L. Harrington, Pittsburgh, Pa., assignor
to Blaw-Knox Company, Pittsburgh, Pa., a corporation of New Jersey

Application September 10, 1941, Serial No. 410,291

4 Claims. (CL 37—183)

This invention relates to a sheave block and, in particular, to a sheave block particularly suited for use as the head or upper block of a clamshell bucket or the like, although it is also useful in other applications.

In clamshell buckets which are operated "in the bight of the line"—that is to say, buckets operated by two lines, one termed a closing line and one termed a holding line, both of the lines being reeved entirely through the bucket and their ends carried to an overhead supporting structure through which the hoist power is applied, it is usual in certain types of buckets to have a single sheave for the hold line mounted between two or more sheaves which are used to draw the bucket head towards the closing block which is mounted in some articulated portion of the bucket below. Where this is the case, the leads of the ropes into the bucket must be such as to co-operate with the sheaves in the hoisting mechanism from which the bucket is suspended.

Clamshell buckets are frequently operated from a trolley of a traveling bridge crane, and in such installations it is important that the cable leads from the bucket run vertically, or substantially so, to the hoisting mechanism. It frequently happens that the spacing between the cable leads at the trolley is relatively close. This has led to attempts to improve the construction of sheave blocks in order to obtain corresponding close spacing of the cable leads at the bucket. Venable Patent No. 1,880,608 shows one form of block which has been satisfactorily employed both as an upper block and as a lower block.

In the case of the buckets of the larger capacities, furthermore, another problem is encountered, viz., the limited bearing area of the sheaves on the usual sheave pin or axle which results from the aforementioned efforts to keep the cable runs close together by making the sheaves of the minimum thickness axially. In order to solve this difficulty, several expedients have been proposed, such as mounting the central or holding sheave of the head block on a level above that of the outer or closing sheaves, but this is very objectionable as it makes the bucket height greater and thus sacrifices headroom available beneath an overhead crane.

I have invented a novel form of sheave block particularly suited for use as a head block in clamshell buckets, which overcomes the difficulties outlined above in a simple and highly effective manner. In a preferred embodiment of the invention, I provide a sheave block composed of spaced hanger brackets having bearings for sup-

porting a sheave pin or axle. I mount the central or holding sheave fixedly on the pin and journal the outer or closing sheaves on the pin for rotation relative thereto. I thus provide ample bearing area on the pin to sustain the load applied to the central or holding sheave without reducing the area available for sustaining the loads applied to the pin through the closing sheaves.

10 According to a further feature of the invention, my block is mounted as a unit in the head frame of a bucket or the like and is secured therein by removable means whereby it may be easily installed or removed. In addition, the sheaves are disposed in planes making an angle less than 45° with the axes on which the bucket arms are pivoted. This further assists in bringing the cable leads from the bucket close together so they may extend vertically to the hoisting mechanism on the trolley.

15 The invention may be more fully understood from the following detailed description and explanation referring to the accompanying drawings illustrating the preferred embodiment. In the drawings,

20 Fig. 1 is a view partly in plan and partly in horizontal section through the frame of a clamshell bucket having the sheave block of my invention mounted therein with parts broken away;

25 Fig. 2 is a side elevation with the bucket arms and other parts omitted; line I—I of Fig. 2 illustrates the plane of the section shown in Fig. 1;

30 Fig. 3 is a partial transverse section taken along the plane of line III—III of Fig. 1; and

35 Figs. 4 and 5 are partial sections taken along the planes of lines IV—IV and V—V of Fig. 3.

40 Referring now in detail to the drawings, a head frame 10 for a clamshell bucket is composed of side channels 11 and cross channels 12 welded thereto. The webs of the channels 11 are extended adjacent the ends thereof to receive bearing sleeves 13 welded thereto. Cross shafts 14 are journaled in bearing bushings 15 seated in the sleeves 13 and bucket arms 16 are pivoted on the projecting ends of the shafts 14. The present invention is not concerned with the particular style of the bucket arms nor their mounting on the head frame. It so happens, however, that in the illustrated embodiment the bucket arms 16 have inwardly projecting portions 17 with meshing toothed segments 18 thereon to maintain the proper alignment of the head block and the lower block. The outwardly and downwardly project-

ing portions of the bucket arms 16 are broken off in Fig. 1.

The head frame 10 includes also a deck plate 19 welded to the webs of the channels 11 and 12, and having suitable openings therethrough for the passage of cables arranged in a manner to be described later. Plates 20, 20', 21 and 21' extend across the deck plate 19 and are provided with bearing sleeves 22 in which are journaled longitudinal guide rollers 23 and transverse guide rollers 24.

Hangers 25 are disposed near the sides of the head frame 10, each hanger including a generally longitudinal plate 26 and generally transverse plates 27 and 28 welded to each other and to the channels 11 and 12. The plates 27 and 28 have portions or lugs depending below the bottom flanges of the channels 11 and 12, with aligned holes therethrough for a purpose which will appear shortly. The plates 26 are not perpendicular to the channels 12 but make an angle of more than 45° therewith, and the plates 27 and 28 are similarly disposed relative to the channels 11.

Referring now more particularly to Figs. 3 through 5, a sheave block indicated generally at 30 comprises a pair of spaced plates or bearing brackets 31 and 32 secured in parallel relation by bolts 33 having spacer sleeves 34 thereon between the plates. Bearing sleeves 35 are suitably secured in aligned openings in the plates 31 and 32 and are provided with anti-friction bearings 36. A sheave pin or axle 37 is journaled in the bearings 36.

The pin 37 has a substantially central enlargement or shoulder 38. A central sheave 39 comprises a hub 40 secured to the shoulder 38 as by welding, and a rim or peripheral portion 41 detachably secured to a flange on the hub by bolts 42. The sheave 39 is rotatable with the pin 37 and the latter turns in its bearings 36 on rotation of the sheave. As illustrated, the hub 40 has a relatively small axial thickness. This is permissible since the sheave 39 does not turn on the pin 37 and there is no need for an extended bearing area.

Outer sheaves 43 and 44 are journaled on the pin 37 between the sheave 39 and the bearings 36. The sheaves 43 and 44 turn on the pin 37 by virtue of anti-friction bearings 45. These bearings extend partly within the planes of the lateral peripheries of the sheave 39, into the space left by making the hub thickness of the latter less than the peripheral thickness. The hubs and bearings of sheaves 43 and 44 are appreciably thicker axially than the hub 40. A guard plate 46 secured to the lower pair of bolts 33 extends around the lower half of the periphery of the sheave 39 and prevents a cable trained around the sheave from leaving the score thereof. A guard plate 47 similarly extends around the upper halves of the sheaves 39, 43 and 44 to prevent cables trained around the sheaves 43 and 44 from leaving the score thereof. The guard plate 47 is cut out as at 48 to clear upwardly extending runs of a cable trained around the central sheave.

The brackets 31 and 32 have ears 49 extending laterally therefrom having aligned holes therethrough. The sheave block 30 may be inserted as a unit in the frame 10 and supported therein by pins 50 passing through the holes in the ears 49 and the holes in the depending portions of the hanger plates 27 and 28, with which they are in alignment. Both the ears and the hanger plates have bearing sleeves 51 welded in

suitable holes therein to provide increased bearing area for the pins 50.

Having described a preferred embodiment, the operation thereof in connection with one form of clamshell bucket will be explained. In addition to the head frame 10 and the sheave block 30 mounted therein, the usual clamshell bucket application requires the use of a lower block, for example, that shown in Venable Patent No. 1,880,608, secured to an articulated joint connecting the bucket halves. A holding line 52 is trained around the central sheave 39 of the upper block from a hoisting drum, for example, to a fixed anchorage on the crane trolley. The closing line 53 extends downwardly from a hoisting drum or the like between pairs of adjacent guide rolls 23 and 24 and through a guide 54a secured to the bracket 31 directly around one of the outer sheaves of the lower block, thence around outer headblock sheave 43, the central sheave of the lower block, headblock sheave 44, the other outer sheave on the lower block, and thence upwardly through guide 54b and the guide rollers to the trolley. The bucket is operated in the usual manner, i. e., it is closed by taking in the closing line, after which the bucket may be hoisted by taking in both the holding and closing lines, and is dumped by paying out the closing line while securing the holding line.

It will be apparent from the foregoing description and explanation that the invention is characterized by important advantages over conventional sheave blocks for use in clamshell buckets or the like. The center sheave of the block does not turn on the sheave pin so that it requires no extended bearing area thereon. Its hub, therefore, may have an axial thickness much less than that of the outer sheaves. Ample bearing area for supporting the pin is provided by the bearing sleeves carried in the brackets 31 and 32. This leaves ample bearing area for the outer sheaves between the center sheave and the pin bearings while maintaining a close spacing of the outer sheaves relative to the center sheave. As clearly shown in Figure 5, the bearings 45 for the outer sheaves 43 and 44 extend partly within the planes defined by the lateral faces of the periphery of the center sheave 39. This in turn permits the sheaves of the lower block to be positioned close together whereby the cable leads therefrom which extend directly to the hoisting mechanism are closely spaced. The close spacing of the sheaves permits a shorter and smaller axle or sheave pin to be used than would otherwise be required, and this reduces the size and cost of the bearings therefor.

The invention thus provides a compact block construction which is particularly advantageous for use with crane trolleys in which the incoming cable leads are close together. By virtue of the novel construction described, the cable leads between the block and hoist mechanism are substantially vertical so there is little or no tendency for the bucket to twist about its vertical axis when the load is transferred from the closing cable to the holding cable, or vice versa.

A further advantage of the invention is the possibility of removing the block as a unit from the head frame of the bucket. It is not necessary, furthermore, to disturb the guide rollers when removing the sheave block. The center sheave construction, including a hub secured to the sheave axle or pin and a peripheral portion detachably secured thereto, permits removal and

replacement of the latter when worn without the necessity of replacing the sheave pin and hub.

The desired arrangement of the cable leads between the bucket and hoisting mechanism is also aided by the arrangement of the sheaves in the head frame, i. e., with the sheaves rotating in planes making an angle of about 75° with the axes on which the bucket arms are pivoted.

A further advantage lies in the fact that when the loaded bucket is suspended jointly by the closing and holding lines, certain forces applied to the sheave pin are in opposition. Under the conditions mentioned, the force exerted on the pin of the upper block by the tension in the closing line reeved around the outer sheaves is downward, while the force exerted on the pin by the holding line reeved around the center sheave is upward. This permits use of a pin of smaller diameter than would otherwise be necessary.

In summary, the advantages of the invention reside in the minimum overall width of the block, the maximum bearing area for the outer or closing sheaves on the pin with minimum overall length of the latter, and the removability of the block as a unit from the head frame.

Although I have illustrated and described but a preferred embodiment of the invention, it will be understood that changes in the construction disclosed may be made without departing from the spirit of the invention or the scope of the appended claims.

I claim:

1. A head sheave block for clamshell buckets or the like, comprising spaced hanger brackets, a sheave pin extending between said brackets, bearings carried by said brackets in which said pin is rotatably supported, a center sheave secured to said pin adapted to be reeved with the holding cable of the bucket, and outer sheaves rotatably carried on said pin between said first-mentioned sheave and said bearings adapted to be reeved with the closing cable of the bucket, said center sheave having a hub with an axial thickness less than the axial thickness of the center sheave at the periphery, and bearings on said pin for said outer sheaves extending at least partially within the planes in which the lateral faces of the periphery of the center sheave lie.

2. A head sheave block for clamshell buckets

or the like, comprising spaced hanger brackets, a sheave pin extending between said brackets, bearings carried by said brackets in which said pin is rotatably supported, a central sheave including a hub fixedly seated on said pin and having a relatively small thickness axially, a peripheral portion removably secured to said hub, said sheave being adapted to be reeved with the holding cable of the bucket, additional sheaves rotatably carried on said pin, said additional sheaves being adapted to be reeved with the closing cable of the bucket and having bearings on said pin between the hub of said first-mentioned sheave and said pin bearings, the bearings for the additional sheaves extending partly within the planes in which the lateral faces of the periphery of the central sheave lie, and means securing said peripheral portion to said hub, said securing means projecting axially beyond the inner ends of the bearings for the additional sheaves.

3. A head sheave block for clamshell buckets or the like, comprising spaced hanger brackets, means for fixedly maintaining said brackets in spaced relation, a sheave pin extending between said brackets, bearings carried by said brackets in which said pin is rotatably supported, a center sheave secured to said pin and adapted to be reeved with the holding cable of the bucket, outer sheaves rotatably carried on said pin between said center sheave and said bearings and adapted to be reeved with the closing cable of the bucket, said center sheave having a hub with an axial thickness less than the axial thickness of the center sheave at its periphery, bearings on said pin for said outer sheaves extending at least partially within the planes in which the lateral faces of the periphery of the center sheave lie, a head block frame having depending lugs, and pins removably inserted through said lugs and said brackets to secure said block to said frame.

4. The apparatus defined by claim 3 characterized by said first-mentioned means being releasable to permit separation of said brackets after removal of the block from the frame, whereby the sheaves which are rotatable on the pin may be slipped off the ends thereof.

EDWARD L. HARRINGTON.
